UNITED STATES PATENT OFFICE.

WILLIAM P. SAMPLES AND PARKER SELVEY, OF GRAFTON, WEST VIRGINIA.

DESIGN FOR A GRAVE-MARKER.

48,503.

Specification for Design.

Patented Feb. 1, 1916.

Application filed November 17, 1915. Serial No. 62,064. Term of patent 14 years.

To all whom it may concern:

Be it known that we, **WILLIAM P. SAMPLES** and **PARKER SELVEY**, citizens of the United States, residing at Grafton, in the county of Taylor and State of West Virginia, have invented a new, original, and ornamental Design for Grave-Markers, of which the following is a specification, reference being had to the accompanying drawing, forming part thereof.

The figure is a face view of the grave markers, showing our new design.

We claim:

The ornamental design for a grave marker, as shown.

WILLIAM P. SAMPLES.
PARKER SELVEY.

Witnesses:

G. W. FORD,
HUGH WARDER.
